UNITED STATES PATENT OFFICE.

ASA CHANDLER HINSON, OF PIDCOCK RANCH, TEXAS.

STOCK FOR PLOW-TRUCKS.

SPECIFICATION forming part of Letters Patent No. 252,218, dated January 10, 1882.

Application filed May 24, 1881. (No model.)

To all whom it may concern:

Be it known that I, ASA CHANDLER HINSON, of Pidcock Ranch, in the county of Coryell and State of Texas, have invented a new and Improved Stock for Plow-Trucks; and I do hereby declare that the following is a full, clear, and exact description of the same.

The object of my invention is to provide an improved stock and suitable devices for connecting a plow to any pair of wheels and axle forming a part of a wagon, by which simple additional connections a farmer may construct a sulky-plow in a cheap and simple manner; and the improvements consist in devices hereinafter more fully described.

In the accompanying drawings, Figure 1 is a plan view of a sulky-plow formed with my improved connections, and Fig. 2 a side elevation of the same with one of the wheels removed.

The running-gear consists of an axle, A, wheels B, a tongue, C, connected to the axle by hounds C', and bolster D, in a well-known manner.

A seat, E, and foot-board F may be attached to one of the hounds, or to the tongue, in such position as to properly balance the plow by the weight of the driver. A stock is formed of two beams, G G', bolted together at their rear ends and united to the axle at their front ends by hinged connections in a peculiar manner. The hinges are each formed of a plate, H, secured to the upper side of the stock and formed into an eye, h, at its front end. The other portion of the hinge is formed by an ear-plate, I, secured to the axle by a clip, I', of well-known construction, that embraces three sides of the axle, and is held in place by bolts i upon the fourth side. The ear-plates I are perforated in a number of places, one above the other, to receive a bolt, K, that passes through the hinge.

joint of the plates H from one ear-plate to the other. By placing the bolt K in the upper or lower perforations the height of the hinge may be regulated to suit axles of different heights from the ground, and the clips may be shifted upon the axle to suit plows of various sizes.

The plow-beam L is securely bolted or otherwise attached to the beam G of the stock, so as to be held in the line of draft. The upper and rear end of the beam G is provided with an eye-bolt, to which is connected the end of an iron chain, M, the other end of which is connected to a hand-lever, N, pivoted to the rear end of the tongue and bolster, by which means the rear end of the stock may be raised and the plowshare lifted from the ground for passing obstacles.

The lever may be made to engage with a catch, n, secured to the tongue, when it is desired to travel from one part of the field or farm to another.

The double-tree or stretchers may be attached directly to the clevis l of the plow when the plow is in use, and is connected to a hook, 65 c, beneath the tongue of the vehicle when the plow is not in use in traveling.

The operation of the device will be readily understood from the foregoing. One of the horses walks in the furrow, and the plow may be adjusted to cut much or little.

What I claim as new is—

The combination, with the stock G G', plow-beam L, and axle A, of the plates having eyes h, the ear-plates I, having a series of perforations, the clips I', connected at their ends by bolts i, and the bolt k, as and for the purpose specified.

ASA CHANDLER HINSON.
